UNITED STATES PATENT OFFICE.

CONRAD H. ZIERDT, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RELAY.

1,284,026.

Specification of Letters Patent.

Patented Nov. 5, 1918.

Application filed February 20, 1917. Serial No. 129,784.

To all whom it may concern:

Be it known that I, CONRAD H. ZIERDT, a citizen of the United States, residing at Edgewood borough, in the county of Allegheny and State of Pennsylvania, have invented certain new and useful Improvements in Relays, of which the following is a specification.

This invention relates to relays, and more particularly to a vane relay which is responsive for contact operation only to alternating current of a frequency above a predetermined value.

In the accompanying drawings, Figure 1 is a view showing in front elevation one form of relay embodying my invention. Fig. 2 is a view showing in top plan the relay shown in Fig. 1. Fig. 3 is a transverse sectional view taken on the line III—III 20 of Fig. 2.

Similar reference characters refer to similar parts in each of the several views.

Referring now to the drawing, the relay in the form here shown comprises a laminated soft iron core C, and a vane V of non-magnetizable electro-conductive material such as aluminum. The core C is substantially C-shaped as shown in Fig. 2, and the vane V is pivoted at X to swing in the air gap between the two confronting ends of the core. The main body of the core is of one thickness, as shown at the right hand end of Fig. 3, but the two confronting legs R, R are of a greater thickness owing to additional laminations K. These laminations are separated from the other or main laminations by several laminations L of copper or other non-magnetic electro-conductive material.

The confronting ends of the core legs R, R are each provided with three poles P, P' and P². Poles P and P' are formed by cutting back the laminations in the main body of the core at 2, this cut being considerably below the middle of the main core body so that pole P is considerably larger than pole P'. Pole P is provided with a copper ferrule or shading band E, a few of the laminations at the top of the main core body being cut back so that this ferrule fits between the main core body and the lowest of the plates L. Pole P² is formed by the additional laminations K as shown in Fig. 1. Pole P² is considerably larger than pole P', so that pole P² has consider-

ably less reluctance than pole P' for a reason which will appear hereinafter.

Each core leg R is provided with an energizing coil W, which coils are, as here shown, connected in series. The vane V is provided with a contact bar Y which contacts with fixed contact members Y^a. The vane is biased to swing around its pivotal point X in clockwise direction from the position shown in Fig. 3, but is at times 65 swung in opposition to such bias to the position in which it is shown in Fig. 3, in which position the contact members Y^a are bridged by bar Y so that the contact is then closed.

The operation of the relay is as follows: When the coils W, W are traversed by alternating current, a magnetic flux is generated in the core C, which, by virtue of the construction of the core ends, divides into three separate paths when crossing the air gap between the core ends to thread the vane V. One magnetic path is through pole P, the second through pole P' and the third through pole P² and the copper laminations L. The flux traversing pole P combines with that of pole P' to form a rotating magnetic field which tends to force the vane V upwardly, this rotating field being due to the shading band E on pole P. In a similar manner the flux traversing pole P² and the copper laminations L combines with that passing through pole P to form a second rotating magnetic field which, however, tends to force the vane downwardly instead of upwardly. Obviously, when the two rotating magnetic fields are of equal strength, no torque will be exerted on the vane by the core C, but when either of the fields dominates, such field will tend to move the vane in its corresponding direction. In this instance, the pole P² being much larger than pole P', the downward tendency would always dominate were it not for the choking effect produced by the copper laminations L. When copper is placed within an alternating magnetic field so that the flux passes directly through the copper, currents are induced therein which in turn generate a counter-magneto-motive force tending to reduce the flux traversing the copper. This action of the induced currents increases in direct proportion to the frequency of the alternating magnetic field, which frequency if sufficiently increased would ultimately result in 110

a complete choking of the flux traversing the copper. Applying this principle to this relay, it will be seen that the copper laminations L reduce the flux passing through pole P², and that by properly proportioning the copper laminations the effects of the two rotating magnetic fields upon the vane V will be neutralized when the coils W, W are traversed by alternating current of a predetermined frequency, so that the vane will be unaffected by such fields. If, however, the frequency of the current supplied to the coils is increased to a certain higher frequency the rotating magnetic field produced by poles P and P' will dominate to such extent as to force the vane upwardly to cause downward movement of the contact bar Y. Such position of the contact bar is maintained as long as the coils are supplied with alternating current at or greater than this latter frequency. However, when the flow of current through the coils is discontinued or when the frequency of such current is less than this predetermined frequency, vane V is released to allow the contact bar Y to move away from contacts Y^a.

From the foregoing it is manifest that I provide a relay which is selective as to frequency for contact operation, and that such selection is obtained by a single core and a single vane. Obviously, such a simplified construction of relay permits the same to be operated on a minimum amount of current, this being a highly desirable feature especially when a relay is controlled from a track circuit in railway signaling.

Although I have shown and described only one form of relay embodying my invention, it is understood that various changes and modifications may be made therein within the scope of the appended claims without departing from the spirit and scope of my invention.

Having thus described my invention, what I claim is:

1. A relay comprising a magnetizing coil, a core having each end divided to provide two outer poles and an intermediate pole, the outer poles being of different reluctance, a shading band surrounding said intermediate pole to produce in conjunction with the two outer poles two rotating magnetic fields of opposite directions, means for equalizing the effect of said rotating magnetic fields when said coil is energized with alternating current of a predetermined frequency and for causing one rotating magnetic field to dominate when said coil is energized with current above said predetermined frequency, and a vane affected in opposite directions by said magnetic fields.

2. A relay comprising a magnetizing coil, a core, a shading band surrounding an intermediate portion of an end of said core to produce two rotating magnetic fields in

opposite directions, means for equalizing said rotating magnetic fields when said coil is energized with current of a predetermined frequency and for causing the effect of one of said rotating magnetic fields to dominate when said coil is energized with current above said predetermined frequency, and a vane oppositely affected by said magnetic fields.

3. A relay comprising a magnetizing coil, a core, a shading band surrounding an intermediate section of an end of said core, to produce two rotating magnetic fields in opposite directions, a choking member arranged within one of said magnetic fields, and a vane oppositely affected by said magnetic fields.

4. A relay comprising a magnetizing coil, a core, a shading band surrounding an intermediate section of an end of said core, to produce two rotating magnetic fields in opposite directions, means for increasing the counter-magneto-motive force of one of said magnetic fields to cause a weaker rotating field in one direction than in the other when said coil is energized with current above a predetermined frequency, and to equalize said rotating magnetic fields when said coil is energized with current of said predetermined frequency, and a vane mounted for movement between said opposed ends and oppositely affected by said rotating magnetic fields.

5. A relay comprising a vane, contacts controlled by said vane, a core, a magnetizing coil for said core, shading bands surrounding portions of the opposite ends of said core for producing two rotating magnetic fields in opposite directions and of unequal strength when said coil is traversed by alternating current of one frequency, but of equal strength when said coil is traversed by alternating current of another frequency.

6. A relay comprising a coil, a core having the ends thereof arranged in opposed relation, each of said ends being formed with three poles, a shading band surrounding the middle pole of each set to form two rotating magnetic fields in opposite directions and of different strengths, means interposed between two poles of each set for equalizing said rotating magnetic fields when said coil is traversed by alternating current of predetermined frequency and for increasing the counter-magneto-motive force of the corresponding magnetic circuit to cause the other rotating magnetic field to become dominant when said coil is traversed by alternating current above a predetermined frequency, and a vane oppositely affected by said rotating magnetic fields.

7. A relay comprising a laminated C-shaped core, a shading band for each end of the core and interposed between the lami-

nations of said core to divide the same into a plurality of poles of different area, copper laminations interposed between certain of said poles, a non-magnetic electro-conductive member mounted to move between the ends of said core, and contacts controlled by said member.

In testimony whereof I affix my signature in presence of two witnesses.

CONRAD H. ZIERDT.
